UNITED STATES PATENT OFFICE.

LEONARD S. THILL, OF GREAT FALLS, MONTANA.

ORE-FEEDING APPARATUS FOR FURNACES.

1,348,603.

Specification of Letters Patent. Patented Aug. 3, 1920.

Application filed December 4, 1916. Serial No. 135,029.

To all whom it may concern:

Be it known that I, LEONARD S. THILL, a citizen of the United States, residing at Great Falls, in the county of Cascade and 5 State of Montana, have invented certain new and useful Improvements in Ore-Feeding Apparatus for Furnaces, of which the following is a specification.

This invention relates to apparatus for 10 conveying finely ground materials, and particularly to means for feeding finely divided ores to furnaces, especially reverberatory furnaces.

The apparatus embodies in its organization 15 a vessel arranged to receive the charge of fine calcine from a MacDougall or other roaster, and means including a system of valves and conveying-pipes for transferring the material by compressed air into a series 20 of hoppers arranged over the reverberatory furnace.

An object of the present invention is to 25 provide a comparatively simple device of this character, wherein the receiving-vessel can be attached directly under or to the roaster or other source of supply of the 30 finely divided material, and in which the receiving-vessel can be filled and the material completely distributed without the escape of dust or gases.

A further object of the invention is to 35 provide conveying-means wherein the receptacle will receive its charge and the material will be delivered therefrom to its destination quickly and positively.

With these and other objects in view, the 40 invention comprises the novel features of construction more fully described herein-after and shown in the accompanying drawings, wherein:

Figure 1 illustrates a reverberatory furnace and means according to the present invention for feeding ore thereto, most of the parts being shown diagrammatically and the 45 reverberatory furnace being shown in section:

Figs. 2 and 3 illustrate in side view two forms of receiving-vessels;

Fig. 4 illustrates a dust-collecting chamber which is inserted in the system beyond the furnace; and

Fig. 5 is a side elevation of one of the furnace-hoppers and the connections thereto.

The dotted lines in Figs. 1 and 5 of the drawings indicate an adaptation of the con-

struction as actually installed in a metallurgical plant.

As illustrated, the conveying-system comprises a roaster 1, such as a MacDougall furnace, having a discharge-chute 2 adapted to regulably discharge the ground ore into a receiving-vessel 3 from which it is distributed through one or more conveying-pipes 4 to the tops of a pair of hoppers 5, 60 arranged one on either side of a reverberatory furnace 6 and above the same. The ore is forced intermittently through the pipe 4 to the hoppers 5 by compressed air in a manner best understood by reference to Fig. 2. 65 The supply of material to the top of the vessel 3 is regulated by means of a suitable quick-closing valve 7, and the discharge of the material therefrom is controlled by a quick-closing valve 8 at the bottom of the 70 vessel. The receiving-vessel 3 is preferably of the double-cone form shown and has sufficient capacity to hold at least a charge for the furnace 6. Air under suitable pressure 75 for forcing the ore from the vessel 3 through the valved outlet, in the bottom 9 is admitted to the vessel through the pipe 10, having a valve 19' and a suitable pressure gauge 11. To prevent the passage of lumps into the pipe 4, the vessel is furnished near its outlet 80 with a grate 12; and for the purpose of affording access to such grate, a closable hand-hole 13 is provided in the side of the vessel 3. The air displaced from the vessel 3 during filling may pass out through pipe 14, 85 the valve 15 therein being open during such filling. A pipe 16, having a valve 17 near its connection to the main air-supply pipe 10 and a nozzle 18 on its lower end, serves to supply a jet of compressed air to the pipe 4 90 beneath the outlet of the vessel 3, for the purpose of preventing the material from packing or caking while being forced from the vessel 3.

According to the arrangement shown in Fig. 2, the vessel 3 is adapted for connection to pipe 4 with others of its kind, so that there will be a series of these supply-vessels for the distributing pipe 4. In Fig. 3 there is illustrated an arrangement suitable for 100 use when there is but the one receiving vessel 3'.

From the vessel 3, the ore is carried by the pipe 4 to the elevated hoppers 5, into which it is distributed at intervals along their 110 lengths through the valve discharge-pipes 19. From these hoppers 5 which are of

relatively large capacity, the ore passes through numerous closed chutes or pipes 20 onto the hearth 21 of the furnace 6, at intervals along its length, a uniform distribution of the ore in the furnace being in this manner insured. Suitable valves 20' may be provided in the feed-pipes 20.

To separate any dust or powder from the air after it has deposited its ore in the hoppers 5, the air on its return to the blower 22, for re-use, is drawn through a suitable dust collector 23. The separated dust is permitted to fall back into the hoppers 5 through pipe 24, while the clarified air passes out through pipe 25 to the blower 22, which may be connected at its blast-side with the air-supply pipe 10.

In operation, the receiving-vessel 3 is filled from the roaster 1 by opening valves 7 and 15, valves 8, 10' and 17 being closed, of course. The valves 7 and 15 are then closed, whereupon the ore may be conveyed to the hoppers 5 through the pipe 4 by opening the valves 8 and 10'. Packing of the material in the pipe 4 beneath the vessel 3 may be prevented by opening valve 17. Upon reaching the cross-pipes 26 (Fig. 5) the material is divided and an even distribution within the hoppers 5 takes place through the discharge-pipes 19. From the hoppers, the ore may pass through the outlets 20 onto the hearth 21 of the furnace or furnaces as desired, at substantially atmospheric pressure. The spent air is freed in the separator 23 of any dust which it still carries and passes on to the fan 22.

Heretofore, it has been the general practice to convey the finely ground ore from the roasters to the furnaces in the open, for instance in open cars or hoppers. Under such operations it often became almost impossible to work on account of the escaping dust and

gases, and besides, there is considerable loss of material. This method is also expensive in both labor and equipment. With the improved apparatus above described, the objections and difficulties are overcome and provision is made for the handling of finely ground materials in a safe, rapid and economical manner.

I claim:—

1. In apparatus for delivering ore from a roaster to a furnace, the combination of a chamber for receiving roasted ore from the roaster, a hopper connected to the furnace, a conduit between the chamber and the hopper, means for charging the chamber independently of the conduit, a pneumatic medium for passing the charge through the conduit into the hopper, means for separating the pneumatic medium from the charge in the hopper, means for returning the pneumatic medium for passing another charge through the conduit, and means for discharging the hopper independently of the said conduit and said medium.

2. In apparatus for delivering ore from a roaster to a furnace, the combination of a chamber for receiving ore from the roaster, a hopper connected to the furnace, a closed circuit passing through the chamber and the hopper, pneumatic pressure means in the circuit to pass the charge from the chamber to the hopper, means for separating the charge in the hopper from the pneumatic means, and means for discharging the hopper substantially independently of the said circuit.

In testimony whereof I affix my signature in presence of two witnesses.

LEONARD S. THILL.
